(57) **CLAIM**

The ornamental design for a lens for camera, as shown and described.

DESCRIPTION

FIG. 1 is a top, rear and left side perspective view of a lens for camera showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof; and,

FIG. 8 is a top, front and left side perspective view thereof, showing the lens for camera in an environment wherein the lens for camera is combined with a camera.

The broken lines in the drawings are included for the purpose of illustrating environmental subject matter and form no part of the claimed design.

1 Claim, 8 Drawing Sheets
